US00D780153S

(12) **United States Design Patent** (10) Patent No.: **US D780,153 S**
(45) Date of Patent: **** Feb. 28, 2017**

(54) **SPEAKER HOUSING**

(71) Applicant: **Logitech Europe S.A.**, Lausanne (CH)

(72) Inventors: **Branko Lukic**, Menlo Park, CA (US);
Steve Ryutaro Takayama, Atherton, CA (US); **David Yim**, Vancouver, WA (US); **Denis O'Keefe**, Newmarket Co. Cork (IE); **Neil O'Connell**, Portland, OR (US); **Steve McGarry**, Vancouver, WA (US); **Chris LaBrutto**, Fremont, CA (US)

(73) Assignee: **Logitech Europe S.A.**, Lausanne (CH)

(**) Term: **14 Years**

(21) Appl. No.: **29/468,185**

(22) Filed: **Sep. 26, 2013**

Related U.S. Application Data

(63) Continuation of application No. 29/437,807, filed on Nov. 20, 2012, now Pat. No. Des. 706,743.

(57) **CLAIM**

The ornamental design for speaker housing, as shown and described.

DESCRIPTION

FIG. 1 is a front elevation view of a covered housing showing our new design;

FIG. 2 is a second perspective view thereof;

FIG. 3 is a bottom plan view thereof;

FIG. 4 is a top plan view thereof;

FIG. 5 is a front elevation view thereof;

FIG. 6 is a rear elevation view thereof;

FIG. 7 is a right-side elevation view thereof; and,

FIG. 8 is a left-side elevation view thereof.

The portions shown in broken lines form no part of the claimed design.

1 Claim, 7 Drawing Sheets
